UNITED STATES PATENT OFFICE.

CHARLES E. CANDEE, OF NEW YORK, ASSIGNOR OF ONE-HALF TO ALBERT G. STORY, OF LITTLE FALLS, N. Y.

JOURNAL-BEARING FOR CAR-AXLES.

SPECIFICATION forming part of Letters Patent No. 312,430, dated February 17, 1885.

Application filed May 15, 1884. (No model.)

To all whom it may concern:

Be it known that I, CHARLES E. CANDEE, of the city, county, and State of New York, have invented a new and Improved Journal-
5 Bearing for Car-Axles, of which the following is a full, clear, and exact description.

The object of my improved construction is to distribute the friction and strain in journal-
10 bearings over a large extent of surface, so as to save wear upon the journals, and also to support the journal against side strains.

The invention, therefore, consists of the hereinafter described and claimed combinations of parts.

15 Reference is to be had to the accompanying drawings, forming part of this specification, in which similar letters of reference indicate corresponding parts in all the figures.

Figure 1 is a side elevation of a journal-box 20 with my improvements, the side cap being removed. Fig. 2 is a vertical cross-section of the same, and Fig. 3 is a cross-section of the box in modified form. Fig. 4 is a detail view.

The box A is of circular form, having seats 25 a for the springs, and the cap b at the outside is removable, to give access to the interior. Within the box, and cast with it, is an abutment, c, which is of an approximate circular form at its outer periphery, between which 30 and the interior surface of the case is a space that receives the ring B. At the top the abutment c receives in a recess the boxing d, that surrounds the journal e of the axle except at the upper part, where the ring B bears on the 35 journal, as shown in Fig. 4, the boxing being made with ribs d' that take into recesses in the abutment to prevent rotation. The ring B also bears upon three rollers—a large roller, f, and smaller ones, g g—that retain the ring 40 in place against the upward strain of the journal. The roller f has journals seated in boxes h h at front and back of box A, and in a line vertically below the axle-journal, while the side rollers, g, are set in mortises in the abutment c upon fixed axles i. Upon the end of 45 the journal e is a spur-wheel, k, that engages

a toothed ring, l, attached to ring B, so that the rotation of the axle causes a slow movement of the ring.

It will be seen that the friction-ring B being 50 of large diameter compared with the journal e, the surface of contact between the two is small, and that it is continually changing by the rotation of the ring. The abutment c supports the journal e firmly against side strains and 55 lurches tending to twist the axle, so that the friction-rollers are relieved of such strains.

In the modification shown in Fig. 3 the large roller f is at the center of box A, and is formed integrally with a cap, m, that is made with or 60 attached to ring B, and closes the outer side thereof, except that openings m' are made for insertion of spur-wheel k. A smaller roller, g, is journaled in the abutment c on the center line. In both forms the rollers are upon 65 journals that turn in boxes instead of turning on axles, as is usually the case, and the axle-journal e being surrounded by a boxing, d, of hard metal, the wear is taken from the abutment. 70

I prefer to use the gearing to insure rotation of the ring; but the contact of the journal and ring may be alone depended on for that purpose.

Having thus described my invention, I claim 75 as new and desire to secure by Letters Patent—

1. The bearings for journals, consisting of friction-ring B and rollers f g, combined with a box having a central abutment, c, substantially as described. 80

2. In a journal-box, the spur k, combined with friction-ring B, having the toothed ring l, and journal e, substantially as described.

3. The friction-ring B, provided with cap m, and formed integrally with roller f, and 85 also made with openings m', substantially as and for the purpose specified.

CHARLES E. CANDEE.
